CUP

William L. Miller, Skokie, Ill., assignor to Continental Can Company, Inc., New York, N.Y., a corporation of New York

Filed Aug. 9, 1960, Ser. No. 61,673

Term of patent 14 years

(Cl. D44—9)

FIG. 1

Figure 3 is an enlarged fragmentary elevational view illustrating a portion of the finger gripping area of the cup.

I claim:

The ornamental design for a cup, as shown.
